No. 13,885

UNITED STATES PATENT OFFICE.

HENRY LANGER, OF BROOKLYN, ASSIGNOR TO G. L. KELTY & CO., OF NEW YORK, N. Y.

DESIGN FOR A CURTAIN AND UPHOLSTERY FABRIC.

SPECIFICATION forming part of Design No. 13,885, dated May 1, 1883.

Application filed October 20, 1882. Term of patent 7 years.

To all whom it may concern:

Be it known that I, HENRY LANGER, a citizen of the United States, residing in Brooklyn, E. D., in the county of Kings and State of New York, have invented or produced a Design for Curtain and Upholstery Fabrics, of which the following is a specification.

This invention relates to a design for striped curtain and upholstery goods woven as three-ply fabrics, with the same design on both sides, but of different colors.

This design is shown in the accompanying photograph.

The ornamental design of the stripe *a* consists in the groups of diagonal bars inclined alternately in opposite directions, as represented.

The stripes *b* and *c* are similar, and are separated more or less by the plain stripe *d*. The design of the stripes *b* and *c* consists of zig-zags or half-diamond shapes, with small diamonds in the included spaces.

The design of the stripe *e* consists in ranges of zigzag stripes running diagonally across the main stripe. These zigzag stripes alternate in colors—such, for instance, as black, light brown, umber, light brown, black, &c.; but the colors are optional. These zigzag diagonal stripes produce a peculiar and pleasing artistic effect.

The stripe *f* is composed of diagonal bars at intervals and intermediate diamonds in rows.

The stripe *g* is composed of bands of varying colors passing diagonally, and as a whole making up the stripe.

The stripe *h* has a range of hollow diamond figures with spots around the diamonds.

The next stripe is a repetition of the stripe *a*.

I claim as my invention—

1. The ornamental design for the three-ply upholstery fabric, consisting of the stripes *a b c d e f g h*, substantially as described and represented.

2. The ornamental design for the three-ply upholstery fabric, consisting of the stripe *a*, with groups of diagonal bars inclined alternately in opposite directions, as represented.

3. The design for three-ply upholstery fabrics, composed of the ornamental stripes *b c* and the intervening plain stripe, *d*, as represented.

4. The design for upholstery fabrics, consisting of the stripe *e*, composed of ranges of zigzag stripes running diagonally across the main stripe, substantially as represented.

5. The design for upholstery fabrics, consisting of the stripe *f*, having diagonal bars and ranges of diamonds, substantially as represented.

6. The design for upholstery fabrics, consisting of the stripe *g*, composed of bands of varying colors crossing the stripe diagonally, as represented.

Signed by me this 17th day of October, A. D. 1882.

HENRY LANGER.
